United States Patent Office

Des. 206,287
Patented Nov. 22, 1966

206,287

DEROTATION INSTRUMENT

Jean G. Lecuyer, Crystal Lake, Ill., assignor to Chicago
Aerial Industries, Inc., a corporation of Delaware

Filed Dec. 3, 1965, Ser. No. 27

Term of patent 14 years

(Cl. D52—6)

Fig. 1

FIGURE 1 is a front perspective view of an optical derotation instrument showing my new design; and

FIGURE 2 is a rear perspective view thereof; and

FIGURE 3 is a lower front perspective view thereof.

I claim:

The ornamental design for a derotation instrument, as shown.
